COCKTAIL TABLE OR THE LIKE

David P. Zagaroli, 2035 11th Street Court NW.,
Hickory, N.C. 28601

Filed Apr. 16, 1975, Ser. No. 568,510

Term of patent 14 years

Int. Cl. D6—03

U.S. Cl. D6—177

The figure is a front perspective view of the cocktail table or the like showing my new design.

The opposite side of the cocktail table or the like is substantially a mirror image of that shown.

The bottom of the cocktail table is substantially plain and unornamented.

I claim:

The ornamental design for a cocktail table or the like, as shown and described.
